UNITED STATES PATENT OFFICE.

HARVEY B. LINDSAY, OF OAKLAND, CALIFORNIA, ASSIGNOR TO DRY ZERO CORPORATION, OF WILMINGTON, DELAWARE, A CORPORATION OF DELAWARE.

METHOD AND APPARATUS FOR PRODUCING BODIES FORMED OF SEPARATE FIBERS.

Application filed January 9, 1925. Serial No. 1,509.

My invention relates generally to the producing of bodies, such as thermal insulating bodies and cushioning bodies, such as for example bedding mattresses, carpet cushions and upholstery, formed of separate fibers; and, as to one aspect thereof, to the producing of such bodies from relatively highly compressed bales of fiber, as for example, and more particularly, kapok fibers; as to 5 another aspect thereof, to the forming of such bodies of substantially the same density throughout their extent; and, as to still another aspect thereof, to the production of such bodies with a complete, or partial, 10 enclosing covering; this application, in part, being a continuation of my application for U. S. Letters Patent Serial No. 683,087, filed 15 December 27, 1923.

As a preface to the following, and as bearing 20 upon one aspect of my invention, it may be stated that it is highly desirable, the fibers of the compressed bale, and especially in the case of kapok, be separated from the bale with the minimum impairment of the fibers 25 as by crushing, tearing or fracturing, this being of importance not only where a body for thermal insulation is to be produced, but also in the case of the producing of a cushioning structure or body.

Referring to the matter of the provision 30 of the body for thermal insulation purposes it may be stated that according to my demonstrated theory of thermal insulation, transmission of heat through a body composed of 35 separate fibers is governed to a large extent by the degree of microscopic smoothness of those surfaces of the fibers which extend crosswise of the path of heat transmission, and this is due to the action which takes 40 place in such a body wherein the external surfaces of the fibers, as also the internal surfaces thereof when of tubular form, are subject to the bombardment of the rapidly moving gaseous atoms where the insulating 45 material is subjected to heat traversing the air to which the fibers are exposed. These gaseous atoms being heated their external electrons are under violent agitation and 50 transmit, through such agitation, violent agitation to the external electrons of the molecules of the fibers proportional to the length of time they are in contact with the latter, and the converse is true where the fibers are in heated condition, in which case

the external electrons of the molecules of the 55 fibers are in violent agitation and transmit such agitation to the electrons of the gaseous atoms proportional to the length of time the electrons of the molecules of the fibers so violently agitated are in contact with the 60 electrons of the gaseous atoms.

Where the surfaces of the fibers are relatively rough and therefore present microscopic crevices, depressions or projections, the gaseous atoms bound and rebound against the surfaces of such irregularities before escaping, and with each impingement the agitated electrons of the hotter element react on the relatively quiescent electrons of the 70 cooler element, conveying their excess agitation to the latter and thereby transmitting heat. Thus, the smoother, and the less crushed or fractured, the surfaces of the fibers, the less the rebounding of the moving 75 electrons and consequently the less transmission of heat. It is, therefore, desirable to employ fibers having smooth, unimpaired, surfaces, and it is also desirable that the fibers be free of kinks.

As regards the provision of a cushioning body or structure, as (for example) in the case of a mattress, a carpet cushion or a body of upholstery, the resilience and the 80 lasting qualities of the body or structure are reduced proportional to the amount of 85 short and crushed or cracked fibers forming the body and thus it is desired that the fibers in the operation of separating them from the bale and delivering them to the point of assembly to form the body, be 90 maintained unimpaired to as great an extent as possible.

My objects generally stated, are to provide for the separating of the fibers from the bale, with the minimum impairment of the fibers; to provide for the production of a body of the character above stated in quilted or mattress condition; to provide for the producing of the body, or structure, preferably quilted, or mattressed, by a continuous operation producing the article to be formed, in a continuous length, or in any predetermined length; to provide for the production of a body of such material of 100 substantially uniform density; and other 105 objects as will be manifest from the following description:

Referring to the accompanying drawings:

Figure 1 is a plan view, with certain portions omitted, of an apparatus constructed in accordance with my invention and adapted for the practicing of my improved method. Figure 1^a is a similar view, with certain parts broken away, of that part of the apparatus which is omitted in Fig. 1. Figure 2 is an enlarged broken view in vertical section taken through the former-portion of the apparatus, the section being taken at the line 2 on Fig. 1 and viewed in the direction of the arrow. Figure 3 is an enlarged broken sectional view taken at the line 3 on Fig. 1, and viewed in the direction of the arrow. Figure 4 is a view in side elevation of the apparatus shown in the preceding figures. Figure 5 is an enlarged sectional view taken at the line 5 on Fig. 1 and viewed in the direction of the arrow. Figure 6 is an enlarged sectional view taken at the line 6 on Fig. 1 and viewed in the direction of the arrow. Figure 7 is a plan sectional view of the tumbler portion of the apparatus, the section being taken at the line 7 on Figs. 5 and 6, and viewed in the direction of the arrow. Figure 8 is an enlarged sectional view of the measuring device of the apparatus, the section being taken at the line 8 on Fig. 1, and viewed in the direction of the arrow. Figure 9 is a broken sectional view taken at the line 9 on Fig. 1 and viewed in the direction of the arrow; and Figure 10, a broken perspective view of the body or structure produced by the apparatus.

Referring to the particular illustrated apparatus it comprises a device, represented generally at 15, for subjecting the bale of fiber from which the body is to be formed, to such an action that the fibers thereof will be loosened from each other at the outer surface of the bale for movement to the part of the apparatus in which the body to be produced is formed, and without tearing or breaking the fibers. The device 15 which operates by a tumbling action comprises a tumbler drum 16 shown as of cylindrical form mounted at circular, circumferentially disposed tracks 17 thereon, on rollers 18 journaled in spaced relation on a supporting frame 19, the drum 16 being driven in any suitable manner, as for example through the medium of a belt 20 driven from any suitable source.

The drum is provided about its inner surface with a plurality of baffle-forming ribs 21 which extend lengthwise of the drum in preferably substantially equi-distantly spaced relation, as shown (Fig. 6). The ends 22 and 23 of the drum contain centrally-disposed openings 24 and 25, respectively, the opening 24, in the particular arrangement shown communicating with the atmosphere, serving to permit of flow of air into the drum through this end thereof

under the action of suction applied to the opening 25, as hereinafter described, and producing air currents in the drum which entrain the separated fibers and conduct them out of the drum. The drum is preferably several times as long as a bale of the material to be operated upon and contains at its outlet end open-work barriers represented generally at 26 spaced-apart lengthwise of the drum, each of these barriers being shown as formed of two generally triangular portions 27 and 28 arranged relative to each other as shown in Fig. 5, these barriers serving to prevent the bale, or heavy masses of the fibers, from moving in the drum to a position in which they interfere with the desired freedom of movement of the air, and the fibers entrained therein, through the outlet 25. The outlet 25 communicates, through the medium of a revolving joint conduit 29, with the inlet of a suction blower represented at 30 which may be of any desirable construction, as by way of example of the centrifugal type, the conduit 29 being provided with a valve 31 for regulating the flow of air currents therethrough. The outlet of the blower 30 and shown generally at 32 communicates with the inlet end of an outwardly flaring conduit 33 which opens at its outlet into a measuring device represented generally at 34. The measuring device 34 which is provided for the purpose of ensuring substantially uniform flow of the fiber to the former-device, hereinafter described, comprises a cylindrical housing 35 containing openings 36 and 37 in its circumferential side-wall which extends substantially the full length of the latter and form an inlet and an outlet, respectively, for the housing, the inlet 36 communicating with the conduit 33. Located within the housing 35 and concentrically disposed relative to the latter and in spaced relation thereto, is an inner shell 38 provided with an inlet and an outlet 39 and 40, respectively, which extend substantially the full length of the shell and in registration with the inlet and outlet 36 and 37, respectively, of the housing 35. The housing 35 and shell 38 are supported at their ends on a shaft 41 fixed in the upper ends of stationary brackets one of which is represented at 42, the ends of the shell 38 being secured to the shaft 41 as by set screws, as shown of the set screw 43 in Fig. 9. The measuring device also comprises a rotatable interstitial drum structure represented generally at 44 and located within the annular space between the shell 38 and the housing 35, the device 44 comprising a cylindrical side-wall-forming portion 45 of interstitial form, it being preferably formed of wire mesh. The ends of the drum 44 comprise rings 46 connected, and extending concentrically, with the cylindri-

cal portion 45 of the drum 44, these rings projecting radially outwardly beyond the portion 45 and being connected with the outer ends of spokes 47 connected with hub portions 48 rotatably mounted on the ends of the shaft 41 between the end walls of the shell 38 and the end walls of the housing 35. One of the hub portions 48 is shown as provided with a pulley 49 driven from any suitable source, and through the medium of which the drum structure 44 is rotated in the direction of the arrow in Fig. 8. The hubs 48 extend between the shaft 41 and openings 35^a in the ends of the housing 35 as shown of one end of the structure in Fig. 9, and means, represented at 50, are provided for rigidly connecting the housing 35 to the brackets 42. The drum structure 44 also comprises a plurality of 20 radially-disposed parallel fins 45^a provided in a series about the circumference of the side-wall portion 45 and extending within the space defined by the side walls of the housing 35 and drum-portion 45 and the 25 rings 46, these fins which extend parallel with the axis of the drum portion 45 and are preferably equidistantly spaced apart and extend from one ring 46 to the other thereof and close to the inner circumference 30 of the side wall of the housing 35, being preferably of interstitial form, preferably of wire mesh construction.

It will be noted from the foregoing that power applied to the pulley 49 causes the 35 interstitial drum structure 44 to be rotated thereby causing the several compartments provided about the circumference of the drum device 44 to be moved in succession across the paths traversed by the air currents entering shell 38 from the conduit 33 and leaving the shell 38 at its outlet 40; and that the volume of fiber (carried by said air currents) which will be discharged from this device, can be governed by the speed 40 of rotation of the drum.

The outlet 37 of the measuring device communicates with the inlet of a conduit 51 the outlet end of which, and forming a nozzle, extends loosely into the former, hereinafter referred to, and represented at 52. The outlet portion of the nozzle 51 is of 50 general rectangular shape in cross section with its side walls, represented at 53, preferably extending entirely through the former 52 which is likewise of rectangular shape in cross section. The upper and lower walls 54 and 55, respectively, of the nozzle reach short of the outer ends of the walls 53 and terminate a short distance beyond the 55 extreme forward edge of the former 52, as shown in Figs. 1 and 3. In other words, the upper and lower walls of the former 52 overlap the corresponding walls of the nozzle and extend in spaced relation thereto 60 as shown in the drawings. The inside cross

sectional dimensions of the former 52 are greater than the outside cross sectional dimensions of the nozzle 51, the walls of which latter extend, throughout the portions thereof which extend into the former, out of contact with the latter as clearly shown in Figs. 2 and 3, the spaces thus provided between the end walls 53 of the nozzle and the end walls of the former, and represented at 56, being indicated at 57.

Associated with the former device 52 are means for supporting rolls 58 of covering material, as for example, and preferably cloth fabric, to be positioned at opposite sides of the fiber body produced in the former 52, these means comprising standards 59 on which the former 52 is mounted, located at opposite sides of the apparatus and containing notches 60 and 61 in which the ends of the cores 62 and 63 carrying the sheet material 58 are seated for rotation, these notches being disposed, respectively, above and below the plane occupied by the former 52.

The sheet material 58, which, in the particular arrangement shown, is of a width considerably greater than the width of the outlet end of the nozzle 51, extends from the rolls thereof into the former 52 at the upper and lower portions of the latter and 95 into the spaces between the upper and lower walls of the former and the corresponding walls of the nozzle, as shown.

Located beyond the former 52 are feeding means comprising two sets of feed rolls 100 represented at 64, 64^a, 65 and 65^a, journaled at their ends in frame works 67 at opposite sides of the apparatus, these sets of rolls being spaced apart length-wise of the apparatus, and the rolls of each set thereof 105 being respectively disposed above and below the formed body and the upper and lower envelope material. The upper rolls, as shown, are drive rolls having drive connection therebetween as by means of sprocket 110 68 and 69 on the rolls and a sprocket chain 70 engaging these sprockets, driving power being applied to one of the upper rolls, as through the medium of a belt pulley 71 on the roll 65.

The rolls 64, 64^a, 65 and 65^a, are alike as to form and size, each preferably presenting at its ends, laterally beyond the side walls 53 of the nozzle 51, circular disk-like portions 72 which are so spaced apart 115 as to firmly grip between them the lateral edges of the sheet material 58 which extend laterally beyond the side walls 53 of the nozzle. The portions of the rolls intermediate the disk-like portions 72, and indicated at 73, are of such reduced diameter 120 that they are spaced apart a distance sufficiently less than the thickness of the body produced in the former 52, and comprising 125 the mass of fibers and the superposed and 130

underlying sheet material 58, to provide tractive effect; the positioning of the disk-like portions 72 on the rollers 64 and 64^a, as stated, causing the lateral edges of the sheet material 58 to be drawn together into flatwise engagement, at opposite sides of the formed body as represented at one side in Fig. 4, the sheet material 58 thereby enclosing the mass of fibers throughout the upper, lower, and side surfaces thereof.

Means are provided in the apparatus shown for stitching through the body formed of the mass of fibers and the covering material 58 and also for sewing together the lateral edges of the covering material 58, these means being represented generally at 74 and comprising a plurality of stitchers represented at 75 which may be of any suitable construction, such as are commonly used in the manufacture of stitched pads of various kinds, and sewing devices located in line with the disk-like portions 72 at opposite sides of the apparatus and represented at 76, these devices being of any desirable construction for sewing together in flatwise condition, the lateral edges of the sheet material 58.

A description of the operation of the illustrated apparatus is as follows:

- 30 Assuming a bale of fiber is introduced into the tumbler device 15, the operation of the suction blower 30 draws the fibers, separated from the bale by the tumbler action, out of the drum 16 and thence into the blower 35 from which they are discharged into the conduit 33 and into the compartments presented above the periphery of the interstitial drum 44 in which compartments the fibers become deposited. By the rotation of the drum 44 40 the fibers in these compartments, when the latter, in the rotation of the drum, move to a position in which they register with the outlet 40 of the inner shell 38, are blown, by the air-blast entering the shell 38 through 45 the inlet 39, out of these compartments and into the nozzle 51 and thence into the former 52 wherein the fibers become massed into a body within the space defined by the side walls 53 of the nozzle and the sheet material 58, as shown in Fig. 2. It may be here 50 stated that in the initial starting of the apparatus a barrier would be placed across the rear end of the former 52 adjacent the extremities of the walls 53 of the nozzle against 55 which the fibers first blown into the former would impinge, in order that a body of the fiber may be built up. Thereafter the feed mechanism and the stitching and sewing mechanism, hereinbefore referred to, will be 60 set into operation to feed the body composed of the mass of fibers and the sheet material, to carry out of the former and upon a table represented at 77, the assembled mass of fibers and sheet material and stitch or 65 tuft the same to the condition shown in Fig.

10, the operation of producing the body or structure being thereby rendered continuous. It is necessary that the air carrying the fibers into the former 52, be relieved from the former 52 after depositing the fibers 70 therein, and this is accomplished by providing vents in the former formed by preference in both the top and bottom walls of the former 52, the openings in the top wall thereof being represented at 78, it being 75 understood that the air escapes through the sheet material 58 and thence through the openings 78.

Where the product of the apparatus is to be used for thermal insulation it is desirable 80 that the mass produced comprise for each cubic foot thereof approximately one pound of the fibers and accordingly the speed at which the various mechanisms described are driven should be regulated.

85 The provision of the measuring device described is of advantage as thereby a uniform flow of fibers to the former 52 producing a uniformly dense mass of the fibers in the latter, may be effected for any width or size 90 of the body to be produced, as the volume of fibers delivered to the nozzle can be governed by the speed at which the drum of the measuring device is rotated.

95 The subjection of the bale of the fiber to the tumbling action described results not only in the rapid removal of the fibers from the bale, but effects such removal with the minimum danger of impairment of the fibers with the advantage above noted.

100 It may be stated that kapok fibers, which are extremely light and fine, are peculiarly amenable to the treatment above set forth. However, the treatment referred to is useful 105 in the treating of other fibers in approximate proportions to their relative weight, the heavier and coarser the fibers the greater the degree of refractoriness.

110 While I have illustrated and described a particular construction of apparatus embodying my invention and have described my improved method as practiced by a particular apparatus, I do not wish to be understood as intending to limit my invention thereto, as the apparatus may be variously modified and altered and other apparatus employed, without departing from the spirit 115 of my invention.

120 What I claim as new, and desire to secure by Letters Patent, is:

1. In the producing of a body of material formed of separate fibers, the subjecting of a compressed bale of the fibers to a tumbling action for loosening the fibers therefrom and the subjecting of the loosened fibers to a conveying current of air.

125 2. In the producing of a body of material formed of separate fibers, the subjecting of a compressed bale of the fibers to a tumbling action for loosening the fibers

therefrom and the subjecting of the loosened fibers, simultaneously with the tumbling action, to a conveying current of air.

3. In the producing of a body of material formed of separate kapok fibers, the subjecting of a compressed bale of the fibers to a tumbling action for loosening the fibers therefrom and the subjecting of the loosened fibers to a conveying current of air.

10 4. In the producing of a body of material formed of separate kapok fibers, the subjecting of a compressed bale of the fibers to a tumbling action for loosening the fibers therefrom and the subjecting of the loosened fibers, simultaneously with the tumbling action, to a conveying current of air.

20 5. The method of decompressing a compressed bale of fibers which consists in repeatedly bodily raising and dropping the bale to loosen its fibers and removing the loosened fibers at the surface of the bale by subjecting the fibers to a current of air.

25 6. In a tumbler device, the combination of a rotatably mounted drum containing inwardly projecting portions and an inlet and an outlet for air, the outlet for air being in an end wall of said drum, and means in said drum extending transversely thereof for maintaining the bale to be tumbled at all times in spaced relation to said outlet.

30 7. In a tumbler device, the combination of a rotatably mounted drum containing inwardly projecting portions and an inlet and an outlet for air, the outlet for air being in an end wall of said drum, and means in said drum extending transversely thereof for maintaining the bale to be tumbled at all times in spaced relation to said outlet, the effective cross-sectional area of draft at said means being greater than at said outlet.

35 8. In a tumbler device, the combination of a rotatably mounted drum containing inwardly projecting portions and an inlet and an outlet for air, the outlet for air being in an end wall of said drum, and an open-work barrier in said drum and extending transversely thereof for maintaining the bale to be tumbled at all times in spaced relation to said outlet.

40 9. In apparatus of the character set forth, the combination of a conduit, a former device communicating with said conduit, means for subjecting fibers, supplied to said conduit, to conveying currents of air, and means in said conduit for measuring and controlling the supply of fiber to said former device, controllable to vary the volume of fiber per unit of time flowing to said device.

45 10. In apparatus of the character set forth, the combination of a conduit, means for supplying air under pressure to said conduit for conveying fibers therethrough, a former device communicating with said conduit, and

means in said conduit for measuring and controlling the amount of fiber delivered to said former device, controllable to vary the volume of fiber per unit of time flowing to said device.

70 11. In apparatus of the character set forth, the combination of a conduit, a power device for supplying air under pressure to said conduit for conveying fibers therethrough, a former device communicating with said conduit, and rotatable means in said conduit operable without distributing the power supplied to said power device, for measuring and controlling the amount of fiber delivered to said former device.

75 12. In apparatus of the character set forth, the combination of a conduit, a former device communicating with said conduit, means for causing fiber-conducting currents of air to flow through said conduit to said former device, and a measuring device for measuring and controlling the amount of fibers passing through said conduit to said former device.

80 13. In apparatus of the character set forth, the combination of a conduit, a former device communicating with said conduit, means for causing fiber-conducting currents of air to flow through said conduit to said former device, and a measuring device for measuring and controlling, and regulable to vary, the amount of fibers passing through said conduit to said former device.

85 14. In apparatus for the purpose set forth, the combination of a conduit, a former device communicating with said conduit, means for subjecting fiber, supplied to said conduit, to conveying currents of air, and means in said conduit for measuring and controlling the supply of fiber to said former device controllable to vary the volume of fiber per unit of time flowing to said device comprising a housing containing an inlet and an outlet, said conduit communicating with said inlet, an interstitial carrier having compartments arranged to move in succession, across said inlet and outlet, and means for causing fiber-conducting currents of air to flow through the course provided by said conduit and housing.

of air to flow through the course provided by said conduit and housing.

16. In apparatus for the purpose set forth, the combination of a conduit, a former device 5 communicating with said conduit, means for subjecting fibers, supplied to said conduit, to conveying currents of air, and means in said conduit for measuring and controlling the supply of fiber to said former device 10 controllable to vary the volume of fiber per unit of time flowing to said device comprising a housing containing an inlet and an outlet, said conduit communicating with said inlet, an inner shell spaced from said housing 15 and containing an inlet and an outlet substantially registering, respectively, with the inlet and outlet of said housing, an interstitial rotatable drum located in the space between said housing and shell and provided 20 circumferentially with fins spaced apart to form compartments, and means for causing the fiber-conducting currents of air to flow

through the course provided by said conduit and housing.

17. In apparatus of the character set forth, 25 the combination of a conduit, a former device communicating with said conduit, means for subjecting fibers, supplied to said conduit, to conveying currents of air, and rotatable means in said conduit operating in their 30 rotation to measure and control the supply of fiber to said former device.

18. The method of producing a body 35 formed of fibers and of substantially uniform density, which consists in producing a measured flow of fiber to the point at which the body is to be formed by delivering the fibers, by the action of an air current, to a rotatable interstitial carrier and removing the fibers therefrom by the action of an air current, after the drum has made a partial 40 revolution.

HARVEY B. LINDSAY.
